VENTILATING APPARATUS

Andrew G. Orear, Glendale, Calif., assignor to
Trade-Wind Motorfans, Inc., Los Angeles,
Calif., a corporation of California

Application February 10, 1936, Serial No. 63,196

8 Claims. (Cl. 98—43)

This invention relates to ventilators and relates more particularly to ventilating apparatus useful in the kitchens, bathrooms, etc. of residences and in numerous other situations. A general object of this invention is to provide a ventilator or ventilating apparatus that is efficient, quiet, compact and very easily serviced, inspected, etc.

Heretofore the disc or "blade propeller" type fan has been employed to a large extent in residence kitchens and for small commercial applications having relatively small air volume. When this type of fan is used at quiet operating speeds with ducts of appreciable length or having turns or elbows its capacity is decreased rapidly and tends to overload the driving motor. Further, the motor of a typical propeller type fan is in the air stream and subjected to the heat, dust, grease, etc. passing over the same. A blower type fan or centrifugal type fan as heretofore provided and manufactured requires a large space for housing it, and requires the dampening of vibration by providing special mountings for the motor and fan and noise and vibration dampening and absorbing connections with the air ducts, etc. Where the use of ducts to convey the air to or from definite spaces is desirable centrifugal or blower type fans are required to build up sufficient pressure to overcome the friction to air flow in the ducts or duct systems. The inconvenience and added cost of providing the required space for a blower type fan or centrifugal fan, the special mountings and the duct connections necessary for the quiet operation of a typical blower type fan have made it impractical to employ the necessary or required fans in such situations.

Another object of this invention is to provide ventilating unit embodying a blower type fan which unit may be mounted in a very limited space, for example, in a typical wall or ceiling structure, and does not necessitate special costly mountings or special flexible connections and fittings to the air ducts.

Another object of this invention is to provide a ventilator or ventilating apparatus of the character mentioned in which the noise and vibration generated by the motor and fan wheel or rotor are fully damped and absorbed immediately adjacent the points where they are generated.

Another object of this invention is to provide a blower type fan ventilating unit of the character mentioned in which the casing that houses the motor and fan rotor unit and provides the fan chamber, the air inlet and the air outlet, is a compact unit that may be permanently or rigidly

installed and may have direct metal connection with the air duct.

Another object of this invention is to provide a motor driven ventilator or ventilating unit that may be mounted in a wall or ceiling structure to be entirely enclosed within such structure. 5

Another object of this invention is to provide a motor driven ventilator of the character mentioned in which the motor and the blower or fan rotor may be very easily removed for inspection, cleaning, servicing, etc. without disturbing the casing, the wiring, the air duct, or any parts of the ceiling or wall structure. 10

Another object of this invention is to provide a motor driven ventilator of the character mentioned in which the driving motor and the blower or fan rotor constitutes a single unit removably held in the casing by a simple, novel means to be easily and conveniently removed through the outer or inlet end of the casing. 15

Another object of this invention is to provide a motor driven ventilator of the character mentioned that embodies a compact housing structure or casing enclosing the various other parts 25 and formed and proportioned for arrangement in a typical wall structure, for example, a ceiling structure, and between its joists or studs.

Another object of this invention is to provide a motor driven ventilator or ventilating apparatus operable to develop sufficient static pressure to overcome the resistance to air flow encountered in ducts or duct systems, and that is particularly smooth running and quiet making a minimum of sound or noise and not subject to vibration when 30 35 in operation.

Another object of this invention is to provide an improved ventilator of the character mentioned in which the motor is not in the main air stream of the blower but is cooled by a forced 40 or positive draft of air induced into the main air stream of the fan or blower rotor through slots of spaces in the motor mounting.

The various objects and features of my invention will be fully understood from the following 45 detailed description of typical preferred forms and applications of my invention, throughout which description reference is made to the accompanying drawings, in which:

Fig. 1 is a side elevation of one form or embodiment of the invention showing it mounted in a typical building or ceiling structure. Fig. 2 is a bottom view of the apparatus shown in Fig. 1. Fig. 3 is a longitudinal or vertical detailed sectional view of the apparatus illustrated in Fig. 1. 50 55

Fig. 4 is a transverse detailed sectional view taken substantially as indicated by line 4-4 on Fig. 3 with a portion of the rotor in section. Fig. 5 is an enlarged fragmentary detailed sectional view of the vibration absorbing mounting of the motor and rotor unit. Fig. 6 is a vertical detailed sectional view of another form or embodiment of the invention illustrating it mounted in a wall or ceiling structure and Fig. 7 is a view taken substantially as indicated by line 7-7 on Fig. 6 illustrating certain parts in transverse cross section.

In the drawings I have illustrated typical embodiments of the invention mounted in a typical wall or ceiling structure. It is to be understood that the invention is adapted to be embodied in forms for use in various situations and for use in various types of wall, ceiling and building structures. Accordingly, the invention is not to be considered as limited or restricted to the specific forms or applications of the invention illustrated in the drawings but is to be taken as including any features or modifications that may fall within the scope of the claims.

The particular wall or ceiling structure illustrated in Figs. 1 to 5 of the drawings comprises the usual horizontally spaced wooden joists 10 which support a sub-floor 11 and a finished floor 12. Lath 13 is secured to the lower sides of the joists 10 and plaster 14 covers the laths. The apparatus or ventilating unit of the present invention is adapted to be arranged in the wall or ceiling structure between two spaced joists 10 and between the sub-floor 11 and the lath and plaster 13 and 14. An opening 15 is provided in the lath and plaster 13 and 14 between the joists 10 to receive the unit. In the particular case illustrated the opening 15 is substantially equally spaced between two joists 10, it being understood that the opening may be otherwise disposed, if desired. In the particular application of the invention about to be described it is preferred to provide a wooden frame 16 in the opening 15 to facilitate the mounting of the ventilator, it being understood that the frame 16 is not essential in all installations. The frame 16 may be built in the wall or ceiling structure at the time of its erection but is not necessary where the ventilator is to be employed in a previously constructed wall or ceiling. The frame 16 is rectangular and, if desired, may be attached to or connected with the joists 10.

The embodiment of the present invention illustrated in Figs. 1 to 5 of the drawings includes, generally, a housing or casing 17 supported by the frame 16 to be within the space defined by the spaced joists 10, the sub-floor 11 and the lath 13, a motor and fan rotor unit 18, and a vibration absorbing means 19 for mounting the unit 18 in the casing 17.

The casing 17 is provided to house the motor and fan rotor unit 18, to provide the blower or fan chamber, and the inlet and outlet for the fan chamber. The casing 17 is preferably sectional comprising a principal section or main section 20, an end plate 21 for the section 20 and an upper section 22. In accordance with the broader aspects of the invention the sections 20 and 22 and the plate 21 may be formed of any suitable material. In practice it has been found desirable to make the section 20 and the plate 21 in the form of castings of aluminum or the like and to form the section 22 of sheet metal. The main section 20 is cylindrical in its general external configuration. The casing section 20 is

tubular or hollow having the blower chamber or fan chamber 23. The side wall of the chamber 23 is substantially vertical and is volutely curved or in the nature of a scroll wall to promote the efficiency of the fan or blower as is well understood by those skilled in the art. The chamber 23 has an opening 24 in its volute side wall between its portions of the largest and smallest radii. The opening 24 is the outlet to discharge the air handled by the fan or blower. A flange 25 may be provided on the section 20 around the outer end of the outlet opening 24 and the wall of the opening 24 and the flange 25 are extended upwardly and outwardly at the upper end of the opening 24 as shown in the drawings. An air duct or discharge conduit 26 is secured to the flange 25 to receive the air from the outlet opening 24. In accordance with the invention this duct 26 may be of metal or any other desired material and may be directly secured to the flange 25 as by bolts or screws 27. The duct 26 may extend to discharge at any desired point.

The lower end of the casing section 20 is provided with an internal recess 28 and an external flange 29. In the particular case illustrated in the drawings the recess 28 and the flange 29 are polygonal or octagonal it being understood that they may be of any desired shape. The recess 28 is open to or in communication with the outlet opening 24 and the fan opening or chamber 23. An adapter 30 is shown mounting or securing the casing section 20 to the frame 16, it being understood that the adapter 30 may be varied to suit various conditions and in some cases may be eliminated. The lower end of the flange 29 may directly bear on the adapter 30 and the section 20 may be secured to the adapter 30 by screws 31. In the structure illustrated in the drawings the adapter 30 has upwardly projecting wings 32 and screws 33 pass through openings in these wings 32 and thread into openings in the flange 29 to further secure the section 20 to the adapter. The adapter 30 fits in the frame 16 and has outwardly projecting horizontal flanges 34 at its lower end secured to the frame 16 by screws 35, or the like. The adapter 30 serves to mount or support the section 20 of the casing 17 directly on the frame 16 of the wall or ceiling structure.

The principal or main casing section 20 may be provided with an integral wiring box or pull box 36 to receive the leads 37 to the fan operating motor, the power supply conductors 38, the splices between the leads 37 and the supply lines 39 and any other required electrical fittings. In the form of the invention illustrated the box 36 projects from the side of the section 20 adjacent the outlet flange 24. Openings 39 are provided in the walls of the box 36 to receive the supply lines 38 and their conduit or conduits 40. The interior of the box 36 is accessible through an opening 41 in its lower end which communicates with the recess 28. An opening 42 may be provided in the outer side of the box 36 and may be normally closed by a removable cover plate 43.

The end plate 21 partially closes the lower end of the fan chamber 23 and has an opening 44 forming the inlet for the fan chamber 23. The plate 21 is removably received in the recess 28, the recess being proportioned to fully or entirely receive the plate. The plate 21 conforms, generally, to the configuration of the recess 28 and is secured to the section 20 by suitable screws 45 threaded into openings in the lower end of the section. The end plate 21 is provided with a web 47 closing the lower opening 41 in the pull box 36.

36. In the preferred construction illustrated in the drawings the plate 21 closes the lower side of the outlet 24. A tongue 48 projects outwardly from the plate 21 and closes or forms the wall 5 of the lower end of the outlet 24. The tongue 48 fits over the adapter 30 and is curved upwardly and outwardly to facilitate the easy positioning and removal of the end plate 21. The upper surface of the plate 21 is provided with a recess 49 10 whose outer wall conforms to the outer wall of the volute fan chamber 23. The recess 49 may extend inwardly to adjacent the inlet opening 44 and is provided to receive any foreign matter, grease or oil that may fall from the fan rotor. Further, the 15 recess 49 may be shaped so that the plate 21 offers a minimum resistance to air flow in the fan chamber 23. The upper side of the tongue 49 may have an inclined surface 50 sloping upwardly and outwardly from the recess 49 to the duct 26.

20 The upper section 22 of the casing 17 is arranged on the upper end of the main section 20 to enclose the driving motor of the unit 18. The section 22 is a cup-like part having a substantially cylindrical side wall and a substantially 25 flat horizontal upper wall. The upper end portion 51 of the main section 20 is cylindrical and reduced in diameter and the lower end portion of the upper section 22 engages or telescopes over this cylindrical part 51. Suitable screws 52 may 30 removably secure the section 22 to the reduced part 51 of the section 20. A vertical opening 53 extends through the reduced part 51 and communicates with the fan chamber or blower chamber 23 and the interior of the casing section 22.

35 The opening 53 and the interior or opening of the section 22 are concentric or aligned with the inlet opening 44. It is preferred to provide a plurality of spaced openings 54 in the upper portion of the casing section 22 to provide for the cooling or 40 ventilating of the motor as will be hereinafter described.

The motor and fan wheel or rotor unit 18 is removably mounted in the casing 17 by the vibration absorbing mounting means 19. The removable unit 18 includes a driving or operating motor 55 and a fan wheel or fan rotor 56. The motor 55 may be an electric motor of the desired or necessary rating, etc. The motor 55 includes a typical case comprising two bell-like sections 57. The motor 55 is arranged longitudinally in the upper casing section 22 and has suitable clearance with its internal walls.

The fan wheel or rotor 56 is preferably of the centrifugal type and may include a flanged hub 58 fixed to the motor shaft 59 by a set screw 60. The blower or fan rotor 56 has impellers or impeller blades 63 extending between a plate 61 and a ring 62. The blades 63 are transversely curved to be effective in throwing or tangentially discharging the air outwardly from the periphery of the rotor 56. The opening of the rotor ring 62 may be slightly smaller in diameter than the inlet opening 44.

The unit 18 is mounted in the casing 17 by the means 19 so that the axis of rotation of the motor shaft 59 and the rotor 56 is substantially concentric with the axis of the inlet opening 44 and so that the periphery of the rotor 56 is relatively close to the side wall of the fan chamber 23 adjacent a side of the outlet opening 24 and the chamber space between the rotor 56 and the wall of the chamber 23 increases circumferentially to a maximum at the outlet opening 24. This positioning of the rotor 56 in the chamber 23 provides for the most efficient handling of the air

by the rotor and for the most efficient compression and flow of air for passage through the outlet 24 and the duct 26. It will be noted that the blower proper or fan proper comprises or is made up of the casing section 20 having the fan chamber 23 and the motor driven fan wheel or rotor in the chamber 23, the casing section 20 being permanently or rigidly mounted, as above described.

The means 19 for mounting the motor and fan rotor unit 18 is an important feature of the invention as it supports the unit 18 in a manner that permits the casing 17 to be permanently or at least rigidly mounted, the means 19 acting to absorb all vibration produced by the motor 55 and the rotor 56 so that no vibration is transmitted to the casing 17 or any parts associated with the casing. The only sounds or noises produced by the apparatus are the magnetic or electrical sounds in the motor 55 and the sound produced by the action of the rotor 56 on the air 20 and these sounds and all other mechanical as well as electrical vibrations are absorbed and damped by the mounting means 19 and are not transmitted to the casing 17. The mounting means 19 supports the unit 18 so that it may be 25 readily removed bodily from the casing.

The improved mounting means 19 includes an upper or inner member 64 and a lower or outer member 65, both of which are secured to the lower or outer end of the motor 55. In practice the members 64 and 65 are annular or in the form of rings. The member 64 is shaped to receive the lower end portion of the lower or outer motor casing section 57 having an annular socket or recess 66 whose wall conforms to and properly cooperates with the motor casing section. The member 64 has a flat face 67 on its lower or outer side which is preferably substantially normal to the axis of rotation of the motor shaft 59. A complementary or abutting face 68 is provided on the upper or inner face of the member 65. A downwardly and outwardly inclined surface 69 is provided on the member 64 and extends inwardly from its periphery. The member 65 has a surface 70 spaced from and substantially parallel with the surface 69. The mounting members 64 and 65 may be directly secured together by screws 9. In the structure illustrated in the drawings screws 71 extend longitudinally through the outer portion of the motor case sections 57, pass through openings in the member 64 and thread into openings 72 in the member 65 to aid in securing the members to the motor. It will be seen that the screws 9 and 71 serve to secure the motor casing sections 57 on the motor 55 and clamp the members 64 and 65 together on the lower or outer end of the motor casing. The members 64 and 65 just described form an element directly engaging and directly secured to the motor 55 and having or providing a space 73 whose walls are inclined with respect to the axis of rotation of the motor shaft 59.

The mounting means 19 includes a ring or member 74 removably secured to the casing 17. In the construction illustrated in the drawings the mounting member 74 is secured to the casing section 20 at the upper wall 75 of the fan chamber 23. The means for removably securing the mounting member 74 to the section 20 comprises spaced parts projecting from the wall 75, which parts may be in the form of screws 76 having heads 77 at their outer or lower ends. Lugs 78 are provided on the periphery of the member 74 and each lug has a slot 79 to receive the screws 76.

16. Bores or depressions 80 are provided on the undersides of the lugs 78 at the inner ends of the slots 79. When the screws 76 are partially threaded outwardly or downwardly the slots 79 5 are adapted to receive the screws. When the member 74 or the unit 18 is positioned where the screws 76 occupy the inner ends of the slots 79 the screws may be tightened or threaded inwardly so that their heads 77 cooperate with the depressions 80 to dependably lock the member 10 74 and the unit 18 associated therewith to the casing 17.

15. The mounting member 74 is provided with an inwardly projecting lip 81. The lip 81 is preferably annular and is provided with flat substantially parallel sides. The lip 81 projects into the space 73 between the members 64 and 65 and is inclined so that its surfaces are substantially parallel with the surfaces 69 and 70. The 20 mounting means 19 includes sections or blocks 25 82 of vibration absorbing material interposed between the surfaces 69 and 70 and the opposing side surfaces of the lip 81. The blocks 82 may be formed of rubber, rubber composition or other material effective in absorbing and dampening vibration. The blocks 82 are preferably spaced apart circumferentially of the assembly of members 64, 65 and 74 and are elongate parts wrapped or turned over the inner circumference of the lip 30 81 to each have substantially equal portions held or interposed between the lip 81 and the surface 69 and the lip 81 and the surface 70. The blocks 82 of vibration insulating material are held in position by being clamped between the surfaces 69 and 70 and the lip 81. It will be seen that tightening of the screws 8 and 71 serves to clamp or hold the blocks 82 compressed between the surfaces 69 and 70 and the lip 81. An upwardly or inwardly projecting annular 40 ridge 83 may be provided on the upper or inner side of the member 74 to positively hold the upper arms or parts of the blocks 82 against outward displacement. It is to be particularly noted that the blocks 82 held between the surfaces 69 and 70 and the lip 81 are inclined relative to the 45 axis of rotation of the motor 55 so that the weight of the unit 18 and vibratory motion resulting from operation of the unit 18 act in lines substantially diagonally of the greatest cross sectional dimensions of the blocks.

50. The blocks 82 of vibration absorbing material support the unit 18 for what may be termed full floating motion, that is, the unit 18 may move a limited extent in any direction relative to the fixed or stationary casing 17. The blocks 82 serve as the sole means for supporting the unit 18 55 on the casing 17 through the medium of the lip 81 and, therefore, fully absorb all vibration resulting from the operation of the motor 55 and the fan rotor 56 so that no vibration is transmitted to the casing 17 or parts associated therewith. In accordance with the invention the spaces between the spaced blocks 82, that is, the portions of the space 73 not occupied by the blocks 82 form air passages connecting the interior of the section 22 with the fan chamber 23. The main stream of air from the fan rotor 56 60 flowing out through the outlet 24 creates a reduced pressure in the upper portion of the chamber 23 and thus induces or draws air inwardly through the space 73. This produces a positive flow of cooling and ventilating air through the casing section 22 to cool and ventilate the motor 55. The air enters the casing section 22 through 65 the openings 54, passes through the chamber of 70 75 the

the section 22 and flows through the space 73 into the main stream of air from the rotor 56.

To permit the ready removal of the motor and fan rotor unit 18 from the casing 17 without disturbing the electrical wiring, a releasable connection 85 is provided in the motor leads 37 at a point between the motor 55 and the box 36. This connection 85 may be in the form of a suitable plug and socket connection capable of being broken or released by pulling apart or unthreading its sections. A suitable grill 86 may be provided over the inlet opening of the adapter 38. The grill 86 obviously may be of any design and character. In the simple form illustrated the grill 86 is a flat grill having a plurality of rectangular openings 87. The grill 86 may be held in position by screws 88 threaded into the frame 16. It is to be understood that the motor 55 of the unit 18 may be controlled by a suitable switch (not shown) at any desired and convenient remote point.

It is believed that the operation of the ventilating apparatus illustrated in Figs. 1 to 5 of the drawings will be readily apparent from the foregoing detailed description. Assuming that the 25 apparatus is mounted or arranged as illustrated and described, its motor 55 may be energized as desired by the closing of a remote convenient switch. During operation of the motor 55 the 30 rotor 56 rotates at a suitable speed in the chamber 23 and its blades 63 operate through a centrifugal action to throw air from the periphery of the rotor thus creating a reduced pressure in the interior of the rotor. A reduced pressure in the rotor of course induces an air flow upwardly 35 through the grill 86 into the intake opening 44 into the rotor. The air thrown or discharged from the centrifugal rotor 56 is compressed and caused to flow outwardly through the chamber 23 through the outlet 24 into the duct 26 and is 40 driven or forced therethrough by the action of the rotor. As previously described the apparatus operates with little or no vibration. The mounting means 19 operates to absorb all vibration produced by operation of the motor 55 and the rotor 45 56 so that such vibration is not transmitted to the casing 17. Accordingly, the casing 17 not being vibrated may be directly connected with the air duct 26 and the supports and mountings without causing the production of vibration and sound in 50 these parts. The recess 49 in the upper side of the end plate 21 dependably traps any grease, foreign matter or oil that may fall from the rotor 56, preventing the passage of such matter into the room.

When it becomes necessary or desirable to service the motor 55 or to clean or service the rotor 56 the unit 18 may be easily bodily removed from the casing 17. To remove the unit 18, the grill 86 and the end plate 21 are first removed. 60 These parts may be easily removed by unthreading their securing screws or bolts. Following the removal of the grill 86 and the end plate 21 the screws 76 may be threaded downwardly or loosened to some extent to disengage their heads 77 65 from the depressions 80. Following this loosening of the screws 76 the unit 18 may be turned slightly to disengage the slots 79 from the screws 76. The unit 18 may then be moved downwardly or outwardly through the casing 17. It is, of 70 course, desirable to break or disconnect the connection 85 so that the wiring of the motor does not have to be disturbed. In practice the leads or wires 37 extending to the motor 55 may be of sufficient length to permit the ready discon- 75

nection of the connection 85. It is to be noted that the removal of the unit 18 from the casing 17 does not necessitate disturbing or loosening the vibration absorbing elements of the mounting means 19. Further, it will be noted that the wiring in the box 36 may be easily inspected and made accessible by merely removing the grill 88 and the end plate 21. The unit 18 is such that it may be easily cleaned and serviced when removed from the casing 17 and the unit may be easily and quickly remounted in the casing 17. The unit 18 may be replaced and secured in the casing 17 as described above by manipulating it so that the inner ends of the bayonet slots 79 receive the screws 76 whereupon the screws 76 may be tightened to bring their heads 77 into the depressions 80. The connection 85 is, of course, preferably made up or connected before the final securing of the unit 18 in the casing.

20 The apparatus illustrated in Figs. 1 to 5 of the drawings may be mounted in various manners and positions other than those shown in the drawings. In certain installations it may be desirable or necessary to support the apparatus by means of hangers secured at their ends to supports such as parts of a wall or building structure, and secured between their ends to the casing section 20 by screws or the like threaded in openings in shoulders 88^a on the section. The flange 29 at the inlet of the casing is particularly adapted to form a mounting or attaching means for the apparatus. The flange 29, if desired, may form the sole or principal mounting attachment for the apparatus and may be directly secured to a wall or building structure, to the duct at the discharge or inlet end of a ventilating or air conditioning system, etc. The flange 25 at the discharge of the casing may also serve as a mounting, if desired. It is to be noted that the mounting means 19 for the unit 18 is such that the apparatus may be mounted with the unit 18 in a vertical position, an inclined position, or a horizontal position without modification of any parts of the apparatus proper.

45 Figs. 6 and 7 of the drawings illustrate a form of the invention embodying a lamp or lighting unit. The casing 17, the motor and fan rotor unit 18 and the mounting means 19 of the apparatus shown in Figs. 6 and 7 may be the same as described above and corresponding reference numerals are employed throughout the drawings for these elements and their several parts. The form of the invention illustrated in Figs. 6 and 7 may be supported by hangers 90 secured at their ends to the joists 10 or other parts of the building structure and secured intermediate their ends to the shoulders 88^a of the casing section 20 by screws or bolts. When the unit or device is supported in this manner the above described adapter 30 may be dispensed with, if desired.

55 The form of the invention being described includes a grill 91 for the air inlet of the apparatus that preferably, though not necessarily, projects downwardly or outwardly beyond the surface of the ceiling or wall, as shown in the drawings. The grill 91 is ornamental in design or configuration and is provided with spaced air inlet openings 92. A flange 93 is provided on the upper end of the grill 91 and may be flush with or may bear against the plaster 14 and is secured to the flange 29 of casing section 20 by screws 94 or the like. The grill 91 thus supported is readily removable to permit the removal of the unit 18 and to provide for easy access to the interior of the apparatus. The grill 91 has a central opening or

socket 95 for carrying a lamp socket 96. An incandescent lamp 97 may be threaded in the socket 96 to project from the lower end of the grill. A bracket or fixture 98 may be provided to carry a suitable globe 99 for the lamp 97. An electric socket 100 is secured to the upper side of the web 47 to project into the box 36. A lead or wire extends from the socket 100 to a suitable remote switch and the other lead from the socket 100 may be connected with a supply line 38. Conductors 101 are provided for the lamp socket 96 and may carry a plug 102. The plug 102 is adapted to be plugged in or pressed in the socket 100 to connect the lamp socket 96 with its supply conductors. It will be apparent that the lamp 97 may be controlled from a conveniently located remote switch.

20 The apparatus illustrated in Figs. 6 and 7 operates in the same manner as the previously described form of the invention. This embodiment 20 of the invention embodies the conveniently and attractively located lamp 97. The grill 91 carrying the lamp 97 and its associated parts may be easily and quickly removed by removing the screws 94 and by pulling the plug 102 from the box or socket 100. Following removal of the grill 91 the end plate 21 may be removed to render the wiring in the box 36 accessible and to permit the easy removal of the unit 18 from the casing 17 in the manner above described.

30 Having described only typical preferred forms and applications of my invention, I do not wish to be limited or restricted to the specific details herein set forth, but wish to reserve to myself any variations or modifications that may appear 35 to those skilled in the art or fall within the scope of the following claims:

Having described my invention, I claim:

1. A ventilating means for installation in a building wall having an opening, the means comprising a casing having a chamber with a volutely curved side wall, the chamber having an open lower end forming an air inlet and having a lateral discharge opening, means for supporting the casing in said opening in the building wall to be entirely within the same and above the plane of the external surface of the wall, and a unit insertable in and removable through the lower end of the chamber, the unit including a centrifugal type blower wheel rotatable in the chamber and related to its volutely curved wall to force air out through the outlet, and a motor above the blower wheel for driving the same, said unit being entirely above the plane of the external surface of the wall.

2. A ventilating means for installation in a building wall having an opening, the means comprising a casing having a chamber with a volutely curved side wall, the chamber having an open end forming an air inlet and having a lateral air outlet, means for supporting the casing to be entirely within the said opening where the said air inlet is open at an external face of the building wall, a unit for arrangement in the casing including a centrifugal type blower wheel, and a motor for driving the wheel, the unit being insertable in and removable through the open end of the chamber, and means removably supporting the unit in the casing to have all of its parts inward of the external surface of the building wall and so that the wheel is in the chamber and is related to its volutely curved wall to force air out through the outlet and the motor is inwardly of the chamber with respect to said external wall.

3. A ventilating means for installation in an

opening in a building wall, said means including, a casing having an inner chamber and an outer chamber, the outer chamber having a volutely curved wall, an open outer end and an air outlet 5 in said volutely curved wall, means for supporting the casing in said opening to be entirely within the same with the open end of the outer chamber open to the atmosphere at the external surface of the building wall, a unit adapted to be 10 inserted in and removed through said open end of the outer chamber and including a motor, and a centrifugal type blower wheel driven by the motor, and means for removably securing the unit in the casing to be entirely housed therein 15 so that the motor and blower wheel are both entirely within the building wall with the motor in the inner chamber and the blower wheel in the outer chamber where it is related to the volutely curved wall to draw air through said 20 open end of the outer chamber and expel it through the outlet.

4. A ventilating means for installation in an opening in a building wall, said means including, a casing having an inner chamber and an outer chamber, the outer chamber having a volutely curved wall, an open outer end and an air outlet 25 in said volutely curved wall, means for supporting the casing in said opening to be entirely within the same with the open end of the outer chamber open to the atmosphere at the external surface of the building wall, a unit adapted to be 30 inserted in and removed through said open end of the outer chamber and including a motor, and a centrifugal type blower wheel driven by the motor, and means for removably securing the unit in the casing to be entirely housed therein so that the motor and blower wheel are both 35 entirely within the building wall with the motor in the inner chamber and the blower wheel in the outer chamber where it is related to the volutely curved wall to draw air through said 40 open end of the outer chamber and expel it through the outlet, the last mentioned means including parts partitioning the inner chamber 45 from the outer chamber.

5. A ventilating means for installation in an opening in a building wall, said means including, a casing having an inner chamber and an outer chamber, the outer chamber having a volutely curved wall, an open outer end and an air outlet 50 in said volutely curved wall, means for supporting the casing in said opening to be entirely within the opening with the open end of the outer chamber open to the atmosphere at the external surface of the building wall, a unit adapted to be 55 inserted in and removed through said open end of the outer chamber and including a motor, and a centrifugal type blower wheel driven by the motor, and means for removably securing the unit in the casing to be entirely housed therein so that both the blower wheel and motor are 60 inward from said external surface of the wall with the motor in the inner chamber and the blower wheel in the outer chamber where it is related to the volutely curved wall to draw air through said 65 open end of the outer chamber and expel it through the outlet, the last mentioned means partitioning the inner chamber from the outer chamber whereby the motor is out of the air stream of the wheel, the said last mentioned 70 means having air ducts connecting the chambers

whereby the air stream of the wheel induces an air current in the inner chamber to cool the motor.

6. A ventilating means for installation in an opening in a building wall, said means including, a casing having an inner chamber and an outer chamber, the outer chamber having a volutely curved wall, an open outer end and an air outlet 5 in said volutely curved wall, means for supporting the casing in said opening to be entirely within the same with the open end of the outer chamber open to the atmosphere at the external surface of the building wall, a unit adapted to be 10 inserted in and removed through said open end of the outer chamber and including a motor, and a centrifugal type blower wheel driven by the motor, means for removably securing the said unit in the casing to be entirely housed therein so that both the blower wheel and motor are inward from said external surface of the 15 wall with the motor in the inner chamber and the blower wheel in the outer chamber and operatively related to said volutely curved wall to force air out through the outlet, and an annular plate secured to the casing at the open outer 20 end of the outer chamber to define the air inlet, the plate having a trap groove facing inwardly with respect to the outer chamber.

7. Ventilating apparatus for installation in a building wall having an opening, the apparatus 25 including, a casing adapted to be inserted through the opening, an adapter to be secured in the opening to support the casing where it is entirely within said opening, the casing having a blower chamber with a volutely curved side wall, 30 an open end forming an air inlet to communicate with the atmosphere at the external surface of the wall and a lateral air outlet, a unit adapted to be passed through said open end of the chamber when the casing is supported in 35 the adapter, the unit comprising a centrifugal blower wheel, and a motor for driving the wheel, and means accessible through said open end of the chamber removably supporting the unit in the casing for removal through the said open end 40 of the chamber for servicing and normally supporting the unit where the wheel is within said chamber in operative relation to the volutely curved wall to force air out through the outlet and the motor is inward of the chamber with 45 respect to its open outer end so that the entire 50 unit is within the building wall.

8. Ventilating apparatus for installation in a building structure ceiling having an opening, the apparatus including, a casing adapted to be inserted through the opening, a flange on the casing fitting the opening to support the casing where it is entirely above the lower surface of the ceiling, the casing having a blower chamber with a volutely curved wall, an open outer end 60 and an air outlet, a blower unit insertable through said open end of the casing, the unit comprising a motor and a centrifugal blower wheel driven by the motor, and means for removably supporting the said unit in the housing to be entirely the said lower surface of the ceiling and where the wheel is in said chamber in operative relation to its volutely curved wall to draw air through the open end of the chamber and force it out through the outlet.

ANDREW G. OREAR.
